SHORTS OR THE LIKE

Irving Flamberg, Mamaroneck, N. Y.

Application October 24, 1956, Serial No. 43,498

Term of patent 14 years

(Cl. D3—17)

FIG. 1.

The broken lines along the sides of the garment indicate side vents formed in the garment.

I claim:

The ornamental design for shorts or the like, substantially as shown and described.
